No. 801,082.

PATENTED OCT. 3, 1905.

G. B. HOCH.

HAME.

APPLICATION FILED DEO. 22, 1904.

UNITED STATES PATENT OFFICE.

GARRICK BRINTON HOCH, OF FREELAND, PENNSYLVANIA.

HAME.

No. 801,082.

Specification of Letters Patent.

Patented Oct. 3, 1905.

Application filed December 22, 1904. Serial No. 237,920.

To all whom it may concern:

Be it known that I, GARRICK BRINTON HOCH, a citizen of the United States, and a resident of Freeland, in the county of Luzerne and State of Pennsylvania, have invented new and useful Improvements in Hames, of which the following is a full, clear, and exact description.

This invention relates to hames for heavy draft-harness, and has for its object to provide novel draft attachments for the wooden bodies of a pair of hames that greatly strengthen them, distribute draft strain equally upon the hames, and facilitate the disconnection of the draft-tug connections from the hames and also the breast-rings therefrom when their worn-out condition necessitates replacement with new ones.

The invention consists in the novel construction and combination of parts, as is hereinafter described and claimed.

Reference is to be had to the accompanying drawings, forming a part of this specification, in which similar characters of reference indicate corresponding parts in all the figures.

Figure 1 is a perspective view of the invention applied upon one of a pair of hames mounted upon a horse-collar and a draft tug-strap or front end of a trace engaged with a detail of the improvement. Fig. 2 is a front view of the improved draft attachment mounted upon an enlarged hame shown broken away above said attachment. Fig. 3 is a transverse sectional view substantially on the line 3 3 in Fig. 2. Fig. 4 is a transverse sectional view substantially on the line 4 4 in Fig. 2. Fig. 5 is a perspective view of a novel construction of pintle-bolt employed, and Fig. 6 is a perspective view of a draft-hook which may be employed.

To show the advantages of the improvement, it may be explained that a pair of heavy draft-hames constructed in the ordinary way are each provided with a draft-hook secured on the wooden body of the hame by a flat looped staple that is inserted through transverse perforations in the hame and secured therein by washers on the limbs of the hames, the ends of said limbs being riveted over the washers, and breast-chain-connecting rings are secured on the hames by mounting them on the staples. The hard service to which the hooks and rings are subjected wears them out in a comparatively short time, and the hames are also in-

jured by wear and unequal draft strain due to the manner in which the draft-hooks are connected with them, as the pulling strain on the securing-staples is liable to split the hames, as well as wear away the rear edges of the hames where the tug-strap hooks rub upon them. The improved means for connecting the tug-straps with the hames distributes the draft strain over the entire width of the hames and also imposes a major portion of the pull upon the forward edges of the same, thus serving to greatly increase the durability of the hames. Furthermore, provision is made for the quick and convenient removal of worn-out tug-strap connections and breast-rings that require renewal, thus lengthening the period of effective service for the hames and their improved connections.

The hames shown at 10 are formed of wood, having the usual shape for engagement with a horse-collar A, and preferably the front and rear edges a' of each hame of a pair are beveled from their front faces rearward and outward, the rear edge a' receiving a reinforcing-strap 10^a, of metal, that is secured thereon by rivets or like means, the strap on each hame terminating at the lower end in an eye b, carrying a ring b' for the reception of a doubled strap 10^b, that secures the lower ends of the hames upon the collar A in the ordinary way.

Upon the flat front face of each hame 10 a bracket-plate 11 is seated at a point suitably removed from the lower end thereof, and upon the forward edge of the bracket-plate an integral flange 11^a is formed, which is extended above and below the bracket-plate and is seated upon the forward beveled edge a of the hame-body. At the longitudinal center of the flange 11^a a hook member 11^b is formed thereon, which laps upon the rear face of the hame, as is clearly shown in Fig. 3, and in service the hook member hugs the bracket-plate 11 closely upon the hame when the flange 11^a is secured upon the edge a of the hame by rivets e. Upon the bracket-plate 11, preferably at an equal distance from the longitudinal center thereof, two similar ears 11^c are formed or secured and project therefrom in parallel planes, said ears being perforated centrally and transversely in alignment.

A pintle-bolt 12 is provided which fits in the aligned perforations in the ears 11^c and is furnished with a head 12^a on one end and a thread on the opposite end, whereon a nut 12^b is

screwed when the pintle-bolt is inserted for service.

On the bolt 12 a clevis 13 is loosely mounted, the members of which have eyes *d* formed on its ends, through which the bolt passes, the head 12^a bearing on one ear when the nut 12^b is screwed into engagement with the other ear. A washer 14 is mounted upon the pintle-bolt 12 between the integral ears *d* when the clevis 13 is placed in position for service, and, as indicated in Figs. 3 and 4, the limbs of said clevis are bent laterally, the concave sides thereof lying adjacent to the strap 10^a, thus affording clearance for the clevis 13 from the hame upon which it is mounted when the tug-strap B is connected therewith and subjected to draft strain.

One end of the bracket-plate 11 is secured upon the hame 10, upon which it is mounted, 20 by a rivet *e*, that passes through it into the hame, this rivet, together with the similar rivet *e* in the flange 11^a, serving to fasten the draft attachment upon the hame, as before mentioned.

25 The head 12^a of the pintle-bolt 12 is in the form of an elongated block formed on one end of the bolt and having a slot *h* in its lower side that inclines therefrom toward the free or outer end of the head, as is clearly shown in Fig. 5, the open end of the slot being closed by the contact of the lower side of the head upon the face of the bracket-plate upon which it seats.

Upon the end of the bracket-plate 11, which 35 affords a seat for the head 12^a of the bolt 12, two ribs *i* are formed longitudinally, these parallel ribs being spaced apart a suitable distance to permit the bolt-head to fit loosely between them when the bolt is inserted through 40 the ears 11^c and eyes *d* and intervening washer 14.

In the slot *h* is loosely fitted a closed breast-ring 15 before the bolt 12 is slid into place, and, as shown in Figs. 2 and 4, said breast-ring rests upon the ribs *i* when the parts of 45 the attachment are assembled for use.

It will be seen that as there is a like attachment provided for each of a pair of hames the tug-straps B, each having the usual clip-band B' on its end and furnished with a looped end B², may be readily connected with the clevis 13 if the latter is disconnected from the ears 11^c and has a limb thereof passed through the looped end of the clip-band and again 55 connected with the ears on the bracket-plate 11, as already explained.

In use draft strain applied upon the clevis 13 will be distributed throughout the area of the bracket-plate 11 upon the hame 10, and 60 as the flange 11^a on the bracket-plate is furnished with the hook member 11^b it will be evident that the pulling strain will be largely imposed upon the concave edge of each hame, so that there can be no splitting of the hames.

65 It will be noted that the introduction of the

washer 14 between the eyes *d* will prevent the limbs of the clevis 13 from shifting on the bolt 12 or being bent. Furthermore, the pull on the limbs of the clevis is away from the hames and avoids injury thereto.

70

In case the eyes of the clevis 13 wear upon the pintle-bolts 12 so as to require a renewal of the clevis or of the pintle-bolts this may be quickly effected in an obvious manner, and the breast-rings 15, if worn so as to be unsafe, 75 may be readily removed by a displacement of the pintle-bolts 12 and their reengagement with the eyes *d* after an exchange of new rings for worn-out ones has been made.

75

In Fig. 6 is shown a draft-hook 16, that is 80 of well-known form and that may be substituted for the clevis 13, said hook having an elongated cylindrical hub *m*, that is centrally bored for the reception of the pintle-bolt 12. The hub of the hook is placed in position between the ears 11^c, having the hook-nose 16^a turned up, so as to permit a reliable hooked engagement with the looped end B² of a clip-band B' on a respective tug-strap B, and thus 85 connect the harness-traces, of which the tug-straps are the forward ends, with the collar A 90 and hames thereon for service.

90

Having thus described my invention, I claim as new and desire to secure by Letters Patent—

95

1. The combination with a pair of hames, of a bracket-plate for each hame, seated and secured on the front face thereof, an integral flange on one edge of the bracket-plate, adapted for engaging the concave forward edge of said hame, a hook on the flange that engages the rear side of the hame when the bracket-plate and flange are mounted upon the hame, and means for detachably connecting the bracket-plate with a harness-tug-strap or trace. 105

100

2. The combination with a hame, a bracket-plate seated upon the front face of the hame, and spaced ears on the front face of the bracket-plate, said ears having aligned perforations, of a clevis having eyes on its ends which fit loosely between the ears, a pintle-bolt passing through said ears and eyes, an elongated head on one end of the bolt having a slot therein, ribs on the bracket-plate between which the head is seated, a breast-ring held in 115 the slot by contact with the ribs, means for holding the bolt in place, and means for securing the bracket-plate on the hame. 110

110

3. The combination with a pair of hames, a bracket-plate seated upon the flat front face of each hame, two spaced and perforated ears on the bracket-plate, a clevis having spaced limbs that terminate in perforated eyes, said eyes occupying space between the ears, a pintle-bolt threaded at one end, a nut screwing on said end, a head on the opposite end of the bolt, two parallel ribs on the bracket-plate between which the bolt-head slides, said head having a slot extended from the lower edge thereof, a breast-ring engaging the slot and 120

120

125

125

130

seated upon the ribs when said ring and bolt are in place, and means for securing the bracket-plate on the hame.

4. The combination with a hame, a bracket-plate thereon, an elongated flange on one edge of the plate, engaged with the bevel edge of the hame, an integral hook member on the flange that engages the opposite side of the hame near its edge, and means for securing the bracket-plate and flange on the hame, of spaced and perforated ears on the bracket-plate, a pintle-bolt securable in the ears, a head on the bolt, having a diagonal slot therein, a breast-ring detachably held in said slot, and means for engaging the pintle-bolt between the ears on the bracket-plate for connecting the hame with the draft member of a harness.
5. In a device of the character described, the bracket-plate having an elongated concave curved flange extended at an angle from one side edge thereof for attachment upon the

concaved edge of the hame, and the flat hook member extended below the bracket-plate and spaced therefrom by the flange.

25

6. In a device of the character described, the bracket-plate having spaced perforated ears thereon, the pintle-bolt engaging the ears, the elongated parallel-sided head on the bolt having a diagonal slot therein extended from the edge that seats upon the bracket-plate, the parallel ribs on said bracket-plate between which the bolt-head slides, the breast-ring engaging the diagonal slot and seated upon the ribs, and a nut on the opposite end of the bolt.

30
